H. JUNKERS

FUEL INJECTING NOZZLE

Filed Nov. 17, 1921

Inventor:
Hugo Junkers
by Dr. Klenckow,
Attorney.

UNITED STATES PATENT OFFICE.

HUGO JUNKERS, OF DESSAU, GERMANY.

FUEL-INJECTING NOZZLE.

Application filed November 17, 1921, Serial No. 515,985, and in Germany January 10, 1921.

My invention relates to internal combustion engines and more particularly to the fuel nozzles of such engines in which liquid fuel is injected by solid injection, that is, 5 without the assistance of air and at high pressure, into a charge of compressed air. In such injection devices the fuel, in order to effect the vaporization required for complete combustion, must be injected at a very 10 high pressure as a rule at several hundred atmospheres. Such high pressures necessitate a very careful tightening of the parts supplying the fuel, and all possibility of the formation of air pockets must be obviated as 15 otherwise the injection becomes irregular and the operation of the engine unreliable.

In the injection devices as heretofore constructed, a nozzle body was employed as a rule, having a wide bore and a needle arranged within said bore and partly filling it, so that the fuel could pass to the point of injection through the annular space between the nozzle body and the needle. This construction involves the drawback that the 25 body of the nozzle is deformed in consequence of the high pressure of the fuel so that it is difficult to keep it permanently tight. Further, the velocity of the fuel is comparatively slow on account of the 30 comparatively great cross-sectional area so that bubbles of air and gas will readily form.

In accordance with my invention I obviate these drawbacks by injecting the fuel through the needle which is to this end provided with suitable feed passages. These 35 passages open in the vicinity of the injection point within the tightening faces between the needle and the nozzle body so that the nozzle body is not strained by the inner pressure of the fuel.

In this arrangement it is further possible to connect the fuel supply pipe directly to the needle so that the fuel is conducted at high velocity to the opening of the nozzle 45 without any change of direction and cross-sectional area.

In some cases, it is desirable that the end 50 of the needle adjoining the combustion chamber should be readily exchangeable, for instance where fuel is used which has a tendency to form incrustations or which exerts a chemical destructive action on the metal. The needle is preferably made in two parts

in such wise that the portion which contains the injection ports can be separated from the 55 portion to which the supply pipe is connected. Preferably, the outer part of the needle, that is, the part to which the fuel supply pipe is attached, is formed as a pressure element so as to force the inner part of the needle against the tightening face of the nozzle body. The tightening between the two parts of the needle is effected in such manner that the bore extends uniformly from one part to the other and no extensions and cavities are 60 formed at the joint where air bubbles or the like might collect.

When assembling and forcing the parts of the nozzle against the tightening surfaces, the parts of the nozzle should be prevented 70 from turning about their axes as the ejection openings of the nozzle have to take up a definite position in relation to the axis of the cylinder and which is determined by the form of the fuel jet. Furthermore the fuel 75 supply pipe should be protected against twisting when screwing down the nozzle, as otherwise the supply pipe might be damaged. Therefor, that part of the needle which is connected with the supply pipe, is preferably 80 so formed that it is free to move axially when the means for tightening the nozzle are screwed down but is unable to turn.

In the drawings affixed to this specification and forming part thereof, an embodiment of my invention is illustrated diagrammatically by way of example. In the drawings—

Fig. 1 is a longitudinal section of the nozzle,

Fig. 2 is an elevation of the nozzle body,

Fig. 3 is an elevation of the needle,

Fig. 4 is an end elevation of the needle,

Fig. 5 is a section on line V—V of Fig. 1.

The novel device comprises a nozzle body 95 *b* screwed into the wall *a* of the working cylinder by means of a thread *m*. In an axial bore of the nozzle body *b* a needle in two parts is secured, part *d* containing the ejection ports and part *e* forming the connection with the fuel supply pipe. Inserted between the two parts is an annular washer *c* of copper or other suitable material. Both parts are provided with an axial bore *f* which extends approximately as far 100 as the ejection ports *g*, *h*. The inner end 105

of part *d* is tightened on the nozzle body by means of a conical surface *k*. The ejection ports *g*, *h* branched off the central bore open into the cone *k* and communicate with narrow channels *i* and *j* formed in this surface. The fuel jets ejected through these passages at high velocity meet at the apex of the cone *k*, whereby a very intimate mixture of the fuel is obtained.

10 Owing to the ports *g* and *h* opening into the tightening surface formed in cone *k* the fuel is prevented from entering the spaces between the needle *d* and the body *b*. Up to the point of ejection the fuel flows 15 exclusively in the narrow bore *f* at high velocity so that air bubbles cannot accumulate. At the same time the nozzle body *b* is relieved of all liquid pressure. The cone *k* need be tightly applied against its seat 20 in the body *b* only in the vicinity of ports *g*, *h* and channels *i*, *j*. The area of the tightening surface between the needle and the body *b* is thereby reduced while the specific tightening pressure at the tightening 25 surfaces is increased and the reliability of the tightening is improved correspondingly.

The fuel supply pipe *l* is inserted and brazed in the outer end of part *e* of the 30 needle. The bore in the washer *c* corresponds exactly to the bore *f* of the needle so that the fuel is conducted in an even path from the supply pipe *l* to the ejection ports *g*, *h*.

35 The outer end of the body *b* is threaded and provided with a cap nut *n* which exerts axial pressure on parts *d* and *e* and forces the tightening surfaces of cone *k* against the corresponding faces of body *b*. In order to 40 prevent turning of the needle parts *d*, *e* and twisting of the supply pipe *l* when screwing down or unscrewing cap nut *n*, projections *v* are provided on an enlargement *w* formed on part *e* which are adapted to engage corresponding recesses *z* (Fig. 2) in the 45 threaded outer end of the nozzle body *b*, so that the part *e* is free to move axially in relation to the body *b* but not to turn in it.

50 I wish it to be understood that I do not desire to be limited to the exact details of construction shown and described for obvious modifications will occur to a person skilled in the art.

55 I claim:-

1. Nozzle for liquid and gaseous fuel injection and the like comprising an outer body having a boring conically contracted at one end and an opening at the apex of 60 the cone, a needle fitting by a conical end surface into the cone of said boring, said needle having an axial channel ending short of said conical end, branch channels extending from said axial channel and opening into said conical end surface at points 65

somewhat distant from the base of said conical end, grooves in said conical surface extending from said branch channels to the apex of said conical surface, fuel supplying means directly connected to the said axial 70 channel of said needle and separate means arranged near the outer end of said body for tightening together said cones.

2. Nozzle for liquid or gaseous fuel injection and the like, comprising an outer body having a boring conically contracted at one end and an opening at the apex of the cone, a needle terminating in a conical end surface and having near said end a materially smaller diameter than said boring, said needle being inserted in said boring with said end surface tightly applied against the conical inner wall of said boring, said needle having an axial channel ending short of said conical end and being connected with said conical end surface by branch channels extending from said axial channel and opening into said surface at points somewhat distant from the base of said conical end, grooves in said conical surface extending from said branch channels to the apex of said conical surface and means arranged near the outer end of said body for tightening said cones together. 80 85

3. Nozzle for liquid or gaseous fuel injection and the like, comprising an outer body having a boring conically contracted at one end and an opening at the apex of the cone, a needle in two parts, a front part terminating in a conical end surface, a rear part and fuel supplying means directly connected to said rear part, said needle being inserted in said boring with said end surface tightly applied against the conical inner wall of said boring, said needle having an axial channel ending short of said conical end and being connected with said conical end surface by branch channels extending from said axial channel and opening into said surface at points somewhat distant from the base of said conical end, grooves in said conical surface extending from said branch channels to the apex of said conical surface and means acting on the rear part of said needle for pressing said conical end surface against the conical inner wall of said body. 100 105 110 115

4. Nozzle for liquid or gaseous fuel injection and the like, comprising an outer body having a boring conically contracted at one end and an opening at the apex of the cone, a needle in two parts, a front and rear part, said front part terminating in a conical end surface, said needle being inserted in said boring with said end surface tightly applied against the conical inner wall of said boring, said needle having an axial channel ending short of said conical end and being connected with said conical end surface by branch channels extending 120 125

from said axial channel and opening into said surface at points somewhat distant from the base of said conical end, grooves in said conical surface extending from said 5 branch channels to the apex of said conical surface and means acting on the rear part of said needle for pressing said conical end

surface against the conical inner wall of said body, said rear part and said body being interlocked for preventing relative 10 circumferential movement.

In testimony whereof I affix my signature.

HUGO JUNKERS.
